JOINT FOR WIND MUSICAL INSTRUMENTS

John H. Albrecht, Utica, N. Y., assignor of one-half to Walter A. Bringe, New Hartford, N. Y.

Application September 19, 1934, Serial No. 744,710

2 Claims. (Cl. 84—385)

My invention relates to a joint for wind musical instruments and I declare the following to be a full, clear, concise and exact description thereof sufficient to enable anyone skilled in the art to which it appertains to make and use the same, reference being had to the accompanying drawing in which like reference characters refer to like parts throughout the specification.

The object of the invention is to provide a joint 10 at the neck of a saxophone or other wind instrument, whereby to hold in a removable manner the mouth-piece to the saxophone instrument proper in a hermetically sealed or air tight manner.

Heretofore much difficulty has been experienced in these joints because of the leakage of air at such locations. This is undesirable and effects the tone quality of the instrument. This defect is overcome in the present invention.

The object will be understood more fully by referring to the drawing in which:

Fig. 1 is a plane view of a saxophone, parts being broken away.

Fig. 2 is a detail enlarged view showing a central section of the joint between the neck and saxophone, parts being broken away.

Fig. 3 is a detail enlarged view showing a perspective of one half an annular ring employed, parts in sections.

Referring more particularly to the drawing, the relative parts of the saxophone are shown in the fragmentary view in Fig. 1. Here the mouth piece is designated 1 and the saxophone proper by 2. The union or joint which connects the mouth piece 1 to the instrument proper 2 is at the location of neck 3 and embodies a ring or collar 4 made independent of the other parts.

Ring 4 is made with an external knurled or roughened portion 5, whereby to aid in turning the same. The interior wall is reduced in thickness at 6 to form an annular shoulder 7 that seats upon the counter annular shoulder 8 made integral with the neck part 9 of mouth piece 1. Ring 4 can turn upon shoulder 8, whereby to lock the neck part 9 to part 2 in an air tight manner.

The lower portion of the interior wall of an-

nular ring 4 is threaded at 11 to engage the corresponding threads formed on the upper end 12 of the saxophone proper 2.

A rubber or felt washer 15 is disposed between the upper edge of end 12 and shoulder 8 of neck part 9 of mouth piece 1, whereby to aid in forming a hermetically sealed or air tight joint.

Neck part 9 is made, whereby it forms a sleeve fit with the complementary portion 12 of the instrument proper 2, the neck slipping down into the portion 12, somewhat snugly.

In operation, the neck part 9 is slipped or telescoped into the portion 12 and pushed together until the threads 11 on the upper edge of part 12 meet the threads of annular ring 4, whereby the turning of said ring 4 will draw portion 12 and neck part 9 tightly together with annular washer 15 disposed therebetween.

The above joint or union can be applied to any saxophone or wind instrument without altering the structure thereof as heretofore made.

Having thus described my invention what I claim as new and desire to secure by Letters Patent is as follows:

1. In a joint for wind musical instruments wherein a mouth piece is telescoped to the neck of a wind musical instrument, an annular shoulder formed on said mouth piece, a ring member having a shoulder for cooperating with the shoulder on said mouth piece and means disposed between said shoulder and said instrument neck, whereby to hold said mouth piece neck to said musical instrument neck in a hermetically sealed manner.

2. In a joint for wind musical instruments wherein a mouth piece is telescoped to the neck of a wind musical instrument having threads formed thereon, an annular shoulder formed on said mouth piece, a ring member having a shoulder for cooperating with said first named shoulder, said last named member having threads for engaging the threads on the neck of said musical instrument, and a rubber washer disposed between said shoulder and said musical instrument, whereby to hold said mouth piece neck to said musical instrument neck in an air tight manner.

JOHN H. ALBRECHT.
